YARN TWIST-DETECTING AND ARRESTING DEVICE

Filed July 9, 1949

FIG. 1

FIG. 2

FIG. 3

FIG. 4

FIG. 5

INVENTOR.
HUGH E. HAYS

BY
Thomas R. O'Nally
ATTORNEY.

In Fig. 3, the thread 6 is shown in that position within the balloon in which the running strand has swung inwardly against, and is moving in a direction lengthwise with respect to, the surface 16 or the edge 17 both of which extend (as shown) transversely with respect to the axis of the support 12. However, the element 18 has a pointed portion 19 which extends away from the surface 16 to form a small region therebetween in which a thread may be trapped while moving in the lateral direction with respect to its length indicated by the arrow. As the take-up means continues to pull the strand 6, it becomes wedged tightly between the element 18 and the surface 16, and either breaks or provides the tension which operates an automatic stopping mechanism (not shown).

In Fig. 5 is illustrated a further embodiment of the invention in which the strand 6 traverses the balloon 6b and passes through a ring element 21 positioned near the apex of the balloon and a guide element 23 from a package being unwound to a take-up device (not shown) in the direction of the arrow. The guide element 23 is split at 24 to facilitate the lacing thereof. The strand 6, in undergoing the rotary motion which causes it to form the balloon, passes around the interior periphery of the ring 21. A small leaf-like element or member 25 is pivotably supported along the inner surface of the ring 21. The swingable end portion 26 is curved away from the ring surface and, as shown in Fig. 5, extends toward the right from its pivot 27 so that strand which is traveling in a counterclockwise direction along the inner surface of the ring becomes trapped by the member 25 and the ring. To provide a spring catch for holding the member in a desired position relative to the ring 21, the member may be made of a flexible material and provided with a pin 29 on its surface in engagement with the ring surface for extending into apertures or depressions 30 along the inner surface of the ring. By this arrangement, the member 25 may be positioned in one direction or the other to trap strand traversing the ring 21 in either circumferential direction. The surface of the guide 23, normally traversed by the strand, is preferably approximately centered over the ring 21. The ring 21 is preferably circular although it may take a moderately out-of-round contour such as an oval shape, if desired.

In the production of rayon cakes, for example, the direction of twist in the yarn, i. e. Z or S, is determined by the direction in which the spinning bucket is rotated. Although the direction of twist cannot be thereafter changed by the manner in which the strand is unwound from the package, the direction of twist always corresponds to the direction of the windings within the cake when the cake is supported in an unwinding position in the same axial orientation as when it was formed. When a number of cakes are unwound and a specific orientation is maintained with respect to that established within the spinning buckets, a strand-trapping device such as one as those hereinabove described may be employed when set in the position corresponding to an unwanted direction of twist. In the use of the invention, the yarn may be unwound from the interior or the exterior of a cake or other annular package preferably in unvarying axial orientation with respect to that of their formation so that the strand of the wrong twist unwinds from packages thereof in a direction

which causes it to be trapped by the apparatus herein described.

While preferred embodiments of the invention have been shown and described, it is to be understood that changes and variations may be made without departing from the spirit and scope of the invention as defined in the appended claims.

I claim:

10. A strand guiding and arresting device in combination with a support for an annular wound package, said device being axially spaced from the support beyond a region occupied by a package when resting on said support and comprising an annular member positioned approximately coaxially about the axis of the support and having an inner thread-engaging surface, a swingable element attached to the inner surface of the member, pivotal means for attaching the element to the member, said element being rotatable through approximately 180 degrees with respect to the said inner surface between two operating positions, said element in either position extending laterally with respect to the axis of the support and inwardly from the inner surface of the member to form a generally V-shaped opening therebetween, the end of said element at the large end of the opening being positioned to trap the strand between the element and the member when the strand is moving laterally in one direction with respect to its length and to slidably engage the strand during movement of strand in the opposite direction, and detent means for holding the element in either position.
20. 2. In combination, a strand guiding and arresting device, a support for an annular wound package, said device being generally axially spaced from the support and comprising a strand guiding surface, an element attached to, and extending from, a surface of the device facing generally in a direction extending toward and away from the axis of the support, said second-named surface being disposed between the strand guiding surface and the support, said element extending transversely with respect to the axis of the support and at an angle with the second-named surface to form a V-shaped opening therebetween having its width increasing in a direction which extends transversely with respect to the axis, the end of said element at the large end of the opening being positioned to trap the strand between the element and the second-named surface when the strand is moving laterally in one direction with respect to its length and to slidably engage the strand during movement thereof in the opposite direction.
30. 3. In combination, a strand guiding and arresting device, a support for an annular wound package, said device being axially spaced from the support beyond a region occupied by a package when resting on the support and comprising a strand guiding surface, an element attached to, and extending from, a surface of the device facing toward the axis of the support and disposed between the strand guiding surface and the support, said element extending laterally with respect to the axis of the support and at an angle from the second-named surface to form a V-shaped opening therebetween having its width increasing in a direction which extends transversely with respect to the axis, the end of said element at the large end of the opening being positioned to trap the strand between the element and the second-named surface when the

strand is moving laterally in one direction with respect to its length and to slidably engage the strand during movement thereof in the opposite direction.

4. In combination, a strand guiding and arresting device, a support for an annular wound strand package, said device being axially spaced from the support beyond a region occupied by a package resting on the support and comprising a strand guiding surface, an element attached to, and extending from, a surface of the device facing toward the support axis and disposed between the strand guiding surface and the support, said element extending laterally with respect to the axis of the support at an angle from the second-named surface to form a V-shaped opening therebetween having its width increasing in a direction which extends transversely with respect to the axis, the element and the second-named surface being joined at a small angle to provide positive seizure of the strand within the opening therebetween, the end of said element at the large end of the opening being positioned to trap a strand when the strand is moving laterally in one direction with respect to its length and to slidably engage the strand during movement thereof in the opposite direction.

5. In combination, a strand guiding and arresting device, a support for an annular wound strand package, said device being axially spaced from the support beyond a region occupied by a package when resting on the support and comprising a strand-guiding surface extending transversely and centrally over the support, an element attached to, and extending from, a surface of the device facing toward the support axis and disposed between the strand-guiding surface and the support, said element extending laterally with respect to the axis of the support and at an angle from the second-named surface to form a V-shaped opening therebetween having its width increasing in a direction which extends transversely with respect to the axis, the end of said element at the large end of the opening being positioned to trap the strand between the element and the second-named surface when the strand is moving laterally in one direction with respect to its length and to slidably engage the strand during movement thereof in the opposite direction.

6. In combination, a strand guiding and arresting device, a support for an annular wound strand package, said device being axially spaced from the support beyond a region occupied by a package when resting on the support and comprising a guide having a strand-guiding surface, a swingable element, a pivotal means for attaching the element to a guide, said element being swingable between two positions approximately 180 degrees apart, and when disposed in either position, extending from a surface of the guide facing toward the support axis and dis-

posed between the strand-guiding surface and the support, said element when in either position extending transversely with respect to the axis of the support and at an angle from the guide to form a V-shaped opening therebetween, the end of said element at the large end of the opening being positioned to trap the strand between the element and the guide when the strand is moving laterally in one direction with respect to its length and to slidably engage the strand during movement of the strand in the opposite direction, and detent means for holding the element in either position.

7. In combination, a unitary strand guiding and thread arresting device, a support for an annular wound strand package comprising an arm pivotably adjustable with respect to a supporting means therefore and having a substantially straight elongate rounded strand-guiding surface spaced centrally from the support beyond a region occupied by a package when resting on the support, said strand-guiding surface extending transversely to the axis of the support, a swingable element attached to a surface of the device facing in a direction extending toward and away from the support axis and disposed between the strand-guiding surface and the support, pivotal means for securing the element to said second-named surface, said element being rotatable through substantially a half circle between two operating positions, said element in either of the positions extending transversely with respect to the axis of the support and at an angle from the second-named surface to form a narrow V-shaped opening therebetween having its width increasing in a direction which is lateral with respect to the axis, spring catch means comprising interlocking portions provided on the guide and the element for securing the element in either position, the end of said element at the large end of the opening being positioned in either position of the element to trap the strand between the element and the second-named surface when the strand is moving laterally in one direction with respect to its length and to slidably engage the strand during movement thereof in the opposite direction.

HUGH E. HAYS.
